UNITED STATES PATENT OFFICE

ALLEN F. HEETER, OF CHICAGO, ILLINOIS, ASSIGNOR TO R. H. BUHRKE COMPANY, A CORPORATION OF ILLINOIS

DESIGN FOR A GOLF CLUB

Application filed September 26, 1931. Serial No. 41,232. Term of patent 3½ years.

To all whom it may concern:

Be it known that I, ALLEN F. HEETER, a citizen of the United States, and a resident of Chicago, in the county of Cook and State of Illinois, have invented a new, original, and ornamental Design for a Golf Club, of which the following is a specification, reference being had to the accompanying drawing, forming a part thereof.

In the said drawing:

Fig. 1 is a fragmentary front elevational view of a golf club showing my new design.

Fig. 2 is a fragmentary view of the same when rotated at right angles to the position of the shaft in Fig. 1, it being noted that a

portion of the club head shank appearing in Fig. 1 is broken away for convenience in illustration.

Fig. 3 is a front elevation of the complete club, but on a reduced scale.

The dominant feature of applicant's design resides in the particular ornamental shaft as shown.

I claim:

The ornamental design for a golf club as shown and described.

In witness whereof, I have hereunto subscribed my name this 21st day of Sept., A. D. 1931.

ALLEN F. HEETER.
